UNITED STATES PATENT OFFICE.

EDGAR D. DICKINSON, OF SCHENECTADY, NEW YORK, ASSIGNEE TO GENERAL ELECTRIC COMPANY, A CORPORATION OF NEW YORK.

GOVERNING MECHANISM.

Application filed September 30, 1921. Serial No. 504,530.

To all whom it may concern:

Be it known that I, EDGAR D. DICKINSON, a citizen of the United States, residing at Schenectady, in the county of Schenectady, State of New York, have invented certain new and useful Improvements in Governing Mechanism, of which the following is a specification.

The present invention relates to governing mechanisms for prime movers, such as steam turbines, for example, and particularly to governing mechanisms of the type employed to automatically shut off the supply of elastic fluid to prime movers in case of excess speed, such mechanisms being ordinarily termed emergency governors.

It relates especially to emergency governors of the type comprising a mass supported on a rotating shaft with its center of gravity outside the axis of rotation of the shaft, the mass being restrained from movement by a suitable spring. At normal speed the mass remains stationary but in case of excess speed it is caused to move outwards or transversely to the shaft by centrifugal force and engage with a tripping mechanism which upon being moved effects the closing of a valve mechanism, such as an emergency valve, thereby shutting off the supply of motive fluid to the prime mover.

Such governors operate in case of excess speed, being set for a speed a suitable or desired amount above normal, for example, 5 per cent above normal. It is desirable, however, to be able to test them without requiring the overspeeding of the prime mover and the object of my invention is to provide means in connection with a governor of this general type whereby this result may be accomplished in a simple and expeditious manner.

In carrying out my invention I provide in connection with the centrifugally operated mass, a means whereby its radius of gyration may be increased in length to effect movement of the mass at a speed lower than normal to trip the emergency valve mechanism. This result may be obtained in various ways such as by adding a weight to the mass, taking weight away from the mass, or shifting the position of a weight carried by the mass, the essential thing being that the radius of gyration be increased. Preferably, I carry out my invention by adding a suitable weight to the mass when

it is desired to test the governor, the weight of course being added at a point which will increase the radius of gyration, as this is a simple and easy way to accomplish the desired result and possesses certain advantages which are pointed out hereinafter.

For a consideration of what I believe to be novel and my invention, attention is directed to the accompanying description and the claims appended thereto.

In the drawing, Fig. 1 is a transverse sectional view of an emergency governor embodying my invention, and Fig. 2 is a side elevation.

Referring to the drawing 5 indicates a revolving shaft such as the shaft of an elastic fluid turbine. In the shaft is a transversely extending opening 6 counterbored for the greater portion of its length to provide a shoulder 7 and located in opening 6 is a plunger 8 which forms the moving mass of the governor. Plunger 8 extends entirely through opening 6 and is provided at one end with a head 9 and at the other end with a reduced portion 10 which slides in a bushing 11. Bushing 11 fits the small end of opening 6 and has a flange 12 which lies against shoulder 7. The other end of plunger 8, i. e., the end provided with head 9, is guided by a bushing 13 held between two annular collars 14 and 15 which are mounted on shaft 5 and fastened together by bolts 16. The collars are provided with semi-circular recesses to receive bushing 13, the latter having an annular groove 17 into which project tongues 18 on the collars whereby the bushing is held in fixed position. Bushing 13 is provided with a tubular extension 19 which projects into opening 6 and is threaded on its outer surface to receive a nut 20. The end of plunger 8 remote from head 9 is threaded at 21 to receive a nut 22 and between nuts 20 and 22 is a spring 23 which serves to hold plunger 8 in opening 6. Nut 22 is fixed to plunger 8 by a pin 24, but nut 20 is adjustable along extension 19 so that the tension of spring 23 can be adjusted. The spring may be adjusted by turning bushing 13, nut 20 being held from turning by a pin 25 which is carried by the nut and slides along a groove 26 in the wall of opening 6. Adjacent head 9 is a trip finger 27 which when moved from under the end of a rod 28 permits rod 28 to move to actuate an emergency valve mecha-

nism (not shown). Spring 23 is set so that at normal speeds plunger 8 will be held from movement but in case of abnormal speeds for example, a speed 5% or 10% above normal, plunger 8 will be thrown out by centrifugal force against the action of spring 23, strike trip finger 27 and effect the closing of the emergency valve mechanism.

The center of the shaft, i. e., the axis of rotation, is indicated at A and the center of gravity of plunger 8 lies above A in the position of the parts shown in Fig. 1. Now, according to my invention, I provide means whereby the center of gravity of plunger 8 may at will be moved further from the axis of rotation and to this end I may either subtract weight from the lower end of plunger 8 or add weight to the upper end. Preferably I do the latter and to this end the head 9 of plunger 8 is threaded to receive a testing weight 29 of such mass that it will cause plunger 8 to move outward and strike trip finger 27 at a shaft speed equal to or any desired amount below normal. It will thus be seen that I can at any time test the emergency governor without the necessity of overspeeding the prime mover. The end of head 9 projects sufficiently far beyond the outer surface of bushing 13 to permit of the weight being readily screwed into place so that to test the governor it is only necessary to screw weight 29 into position and then bring the prime mover up to the required speed.

Emergency governors are carefully set to trip at a desired speed and it will be seen that by my invention the setting is not disturbed or modified in any way. My invention also makes testing of the emergency governor an easy matter and a thing readily performed by the ordinary engineer. Furthermore, by having testing weight 29 suitably calibrated, i. e., having it of a predetermined weight, the setting of the emergency governor can be varied by noting the speed at which the governor trips with the testing weight thereon.

It will be understood of course, that the testing weight is removed from plunger 8 head 9 during normal operation. It is only placed thereon when it is desired to test the emergency governor mechanism.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. The combination with a rotating shaft

and an emergency governor carried thereby and comprising a mass having its center of gravity to one side of the axis of rotation of the shaft, of means for setting the governor to trip at a speed a predetermined amount higher than normal speed, and means independent of the first named means for effecting movement of said mass at a speed lower than that for which the governor is set by said first named means when it is desired to test the governor.

2. The combination with a rotating shaft and an emergency governor carried thereby and comprising a mass having its center of gravity to one side of the axis of rotation of the shaft, of means carried by the shaft and operatively engaging with the mass for setting the governor to trip at a speed a predetermined amount higher than normal speed, and means independent of the first named means and operating without affecting the setting of said first named means for effecting movement of the mass at a speed lower than that for which the governor is set by said first named means when it is desired to test the governor.

3. The combination with a rotating shaft, of an emergency governor carried thereby comprising a movable mass having its center of gravity to one side of the axis of rotation of the shaft, a spring carried by the shaft which yieldingly holds said mass to a limited movement, means for adjusting said spring to permit the mass to move to a degree required to trip the governor at a speed a predetermined amount above normal, and means independent of said spring adjusting means for effecting movement of the mass at a speed lower than that at which it is adjusted to move by said first named adjusting means when it is desired to test the governor.

4. The combination with a rotating shaft and an emergency governor carried thereby and comprising a mass having its center of gravity to one side of the axis of rotation of the shaft, and spring means carried by the shaft and restraining movement of the mass, of means for adjusting said spring means to set the governor to trip at a speed a predetermined amount higher than normal speed, and means independent of said adjusting means for effecting movement of said mass at a speed lower than that for which the governor is set by said first named adjusting means, said independent means operating without destroying the setting of said adjusting means.

5. The combination with a rotating shaft and an emergency governor carried thereby and comprising a mass having its center of gravity to one side of the axis of rotation of the shaft, and spring means restraining movement of the mass, of means for adjusting said spring means to set the gov-

ernor to trip at a speed a predetermined amount above normal speed, and a weight adapted to be added to the mass to increase the distance between the axis of rotation of the shaft and the center of gravity of the mass whereby the governor is caused to act at a lower speed.

6. The combination with a shaft, of an emergency governor comprising means forming an opening which extends transversely of the shaft, a plunger in said opening having its center of gravity to one side of the axis of rotation of the shaft, a spring which restrains said plunger from movement, means for adjusting said spring to set the governor to trip at a speed a predetermined amount higher than normal speed, and means for effecting operation of said governor at a speed lower than that for which it is set by said spring and without affecting the setting of said spring.

7. The combination with a shaft, of means forming an opening which extends transversely of the shaft, a plunger in said opening having its center of gravity to one side of the axis of rotation of the shaft, a spring carried by the shaft and which restrains said plunger from movement, means for adjusting said spring to cause the plunger to move responsive to a speed a predetermined amount above normal speed, and a second and independently acting means for causing said plunger to move at a speed below that for which it is set to move by said first named adjusting means, said last named means being adapted to act temporarily when it is desired to test the governor and operating without destroying the setting of said adjusting means.

40 8. The combination with a shaft, of means forming an opening which extends transversely of the shaft, a plunger in said opening having its center of gravity to one side

of the axis of rotation of the shaft, said plunger having a head with a threaded portion, a spring which restrains said plunger from movement, and a weight adapted to be screwed onto said head.

9. The combination with a shaft, of an emergency governor comprising means forming an opening which extends transversely of the shaft, a plunger in said opening having its center of gravity to one side of the axis of rotation of the shaft, a spring which restrains said plunger from movement means for adjusting said spring to set the governor to trip at a speed a predetermined amount higher than normal speed, and means including a weight adapted to be fastened to and removed from said plunger for varying the radius of gyration of said plunger whereby the governor may be adjusted for testing purposes.

10. An emergency governor for a rotating shaft comprising a trip element arranged in close relation to the shaft, an eccentrically weighted element carried by the shaft and capable of moving out to engage the trip element, an adjustable spring means cooperating with the weighted element and by which the governor may be set to render the engagement of said weighted element with the trip element responsive to a speed a predetermined amount above normal speed, and means independent of said spring means for causing the weighted element to move out to engage the trip element at a speed below the speed at which the governor is set to trip by said first-named means, said last-named means operating without affecting the adjustment of the spring means and being brought into operation when it is desired to test the emergency governor.

In witness whereof, I have hereunto set my hand this 28th day of September, 1921.

EDGAR D. DICKINSON.
